UNITED STATES PATENT OFFICE.

CHRISTIAN WILLIAM MEINECKE, OF JERSEY CITY, NEW JERSEY, ASSIGNOR
TO MEINECKE & CO., OF NEW YORK, N. Y., A CORPORATION OF NEW JERSEY.

DESIGN FOR A CUSHION.

SPECIFICATION forming part of Design No. 35,654, dated February 4, 1902.

Application filed January 3, 1902. Serial No. 88,361. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Cushion, of which the following is a specification.

My invention relates to a new and original design for cushions, and is illustrated in the accompanying drawings, in which—

The leading feature of my design resides in a cushion having a curved rear portion running into parallel or approximately parallel side portions joining a front portion, said cushion having an oval opening.

In said drawings the letter a indicates the curved rear portion of the outline. The sides are shown at a'. The curve a runs into or joins such sides, and the latter are parallel, or practically so. The front is shown at a'' joining the sides.

The cushion has an oval opening, (shown at b.) said oval having its major axis running from front to back of the cushion, this oval opening being the distinguishing feature of the cushion of this design.

The design presents a cushion having a novel, pleasing, and distinguished appearance.

What I claim as new, and desire to secure by Letters Patent, is—

The design for a cushion substantially as herein shown and described.

In testimony whereof I have hereunto set my hand in the presence of two subscribing witnesses.
